UNITED STATES PATENT OFFICE.

EDWIN A. ROBERTSON, OF SYRACUSE, INDIANA, ASSIGNOR, BY MESNE ASSIGNMENTS,
TO THE PERMUTIT COMPANY, OF NEW YORK, N. Y., A CORPORATION OF DELAWARE.

COMBINED SHEET-METAL TANK AND SUPPORTING BASE.

Application filed June 15, 1927. Serial No. 198,992.

My invention relates to a combined sheet metal tank and supporting base for the tank, made by forming one head of the tank in a supporting base and a tank of suitable size and shape with one head omitted, then placing the open end of the tank element in position on the base element so that the head formed in the base is in proper position to form one end of the tank, then welding the tank to the base.

Such construction makes a light, cheap, seamless structure, using the least possible material, especially adapted to resist corrosion, and this is the principal object of my invention.

The particular embodiment of my invention selected for illustration is a twin tank construction on a supporting base, in which the heads for both tanks are formed, adapted for use on a zeolite water softener.

Figure 1 is a vertical axial section through the tanks and base, the upper ends of the tanks being broken away, and

Fig. 2, is a cross section on the line 2—2 of Fig. 1.

Referring now to the drawings, A is a cylindrical, sheet metal tank in which a bed of zeolite is placed, and S is a cylindrical, sheet metal tank in which salt and water are placed to form brine, the fluid used to regenerate the zeolites when their water softening capacity has become exhausted. B is the sheet metal base whose downwardly turned edge b forms a flange which rests on the floor. A downwardly bulging portion b¹ of the base B is of the same diameter as the tank S, and when the open end of said tank S is fitted in place on the base B, over the de-

pressed portion b¹, the tank and base are welded together all around at b³ forming a leak-tight, seamless joint. In like manner above a similar bulging portion b² is welded all around at b⁴ the open end of the tank A. It will be seen that the bulging portion b¹ of the base B forms the convex bottom head of the tank S, and the bulging portion b² forms the convex bottom head of the tank A.

The light, sturdy structure so formed uses the least possible material, requires little labor and is most efficient in minimizing corrosion. Lapped and riveted joints are omitted, and sharp bends adjacent the weld are avoided in order not to strain the metal unduly.

I claim as my invention and desire to secure by Letters Patent of the United States:—

A metal tank adapted to contain corrosive liquids such as occur in zeolite water softening systems composed of a cylindrical sheet metal shell welded to a sheet metal base, said base having an exterior downwardly turned peripheral flange upon which the structure rests formed contiguous with an intermediate substantially horizontal portion merging into an interior circular depressed portion, said flange and depressed portion being spaced apart thereby avoiding sharp strain-inducing bends in the metal adjacent the junction of the base and shell, said shell being positioned around the circumference of the depressed portion and on said horizontal portion of the base.

In testimony whereof I have hereunto set my hand.

EDWIN A. ROBERTSON.
